(No Model.)

H. LINDESTRÖM.
MOWER.

No. 404,549.

Patented June 4, 1889.

UNITED STATES PATENT OFFICE.

HJALMAR LINDESTRÖM, OF ENGLEWOOD, ILLINOIS, ASSIGNOR OF ONE-HALF
TO AUGUST JERNBERG, OF SAME PLACE.

MOWER.

SPECIFICATION forming part of Letters Patent No. 404,549, dated June 4, 1889.

Application filed September 21, 1888. Serial No. 286,011. (No model.)

To all whom it may concern:

Be it known that I, HJALMAR LINDESTRÖM, of Englewood, in the county of Cook and State of Illinois, have invented certain new and useful Improvements in Mowers; and I do hereby declare that the following is a full, clear, and exact description thereof, reference being had to the accompanying drawings, and to the letters of reference marked thereon, which form a part of this specification.

This invention relates to improvements in cutter-bar-actuating mechanism for mowing-machines of that class wherein reciprocatory movement of the cutter-bar is produced through the medium of a rocking lever which is pivotally supported at its center and provided at its ends with wheels or rollers which engage a scalloped ring-shaped or annular cam upon the main driving-wheel of the machine.

The invention consists in the matters hereinafter described, and pointed out in the appended claims.

A main feature of novelty embraced in my invention consists in constructing the engaging surfaces of the rollers upon the rocking lever and the scalloped cam with gear-teeth or cogs arranged to intermesh with each other. The presence of such intermeshing gear-teeth upon said parts has the advantage of producing an equal wear upon all parts of the wheels and cam, for the reason that the gear-teeth cause the wheels to rotate uniformly, while in the absence of such gear-teeth the wheels are liable to become flattened or unequally worn, especially if there is any slight irregularity in the cam, thereby rendering the entire structure useless and inoperative.

In the accompanying drawings, illustrating my invention, Figure 1 is a plan view of the frame, drive-wheels, and gearing of a mower constructed in accordance with my invention. Fig. 2 is a sectional view of the same, taken upon line 2 2 of Fig. 1. Fig. 3 is a sectional elevation of the cam-wheel upon line 3 3 of Fig. 1. Fig. 4 is a detail section taken upon line 4 4 of Fig. 2. Fig. 5 is a detail view of a wheel provided with an interior instead of an exterior cam. Fig. 6 is a detail section on line 6 6 of Fig. 4.

As illustrated in the said drawings, A indicates the machine-frame, and B B' the main wheels, which are mounted upon an axle B², and one of which B is the drive-wheel of the machine.

C is a rock-shaft mounted in bearings a a upon the machine-frame and provided adjacent to the drive-wheel B with a rocking lever C', having arms of equal length at either side of the rock-shaft and provided at its ends with toothed wheels or pinions D D, which intermesh with a scalloped ring or cam E, secured upon the said wheel B adjacent to the rim thereof, said cam being provided with spurs or teeth intermeshing with those of the wheels or pinions D D. Said wheels or pinions are arranged at such distance apart that when one of the same is engaged with a depression of the scalloped cam the other pinion will be engaged with an elevation thereof. From this construction it is entirely obvious that as the main wheel B rotates the lever C' and shaft C will be given a rocking or oscillatory motion, the said pinions D D being pushed alternately inward as they pass over the elevations of the said cam E. It will of course be understood that as one wheel rises upon or is forced inwardly by the action of one of the elevations the other wheel is thereby moved or pressed into the depression which is opposite to it at the time, the motion transmitted to the cutter-bar being produced by the passing of the wheels alternately over the prominences of the cam.

The oscillatory movement given to the shaft C by the gear described may be transmitted to the cutter-bar in any manner found convenient or desirable. In the particular construction illustrated connecting devices for this purpose are made as follows:

C² is a rigid depending arm attached to the rock-shaft C by the set-screw c', which passes through a hub or projection on the arm C². Said arm is provided with a vertical groove c, Figs. 4 and 6, in one of its faces.

F is a sleeve mounted to slide and also adapted to rotate upon the shaft C, said sleeve being provided with a depending arm F', Figs. 4 and 6.

G is a vertically-arranged hand-lever piv-

oted upon a bracket A' upon the frame and provided at its lower end with prongs g g, which engage pins h h in a collar H, which fits within an annular groove in the sleeve F.

5 By moving said hand-lever the sleeve may be moved endwise upon the shaft, so as to carry the depending arm F' of said sleeve into the groove c of the arm C² or to free said arm F' from said groove. When the arm F' is engaged with the arm C², said arm F' will partake of the oscillatory movement of the rock-shaft. When, on the contrary, the sleeve F is moved so as to free the arm F' from the said arm C² of the shaft, said latter arm will 15 continue to vibrate without giving any motion to the arm F' and connected parts.

It will of course be understood that inter-fitting recesses and projections of any shape upon the arms C² and F' may be substituted for the particular construction shown (embracing the groove c and the edge of the arm F' fitting therein) with the same result.

G' indicates a spring-detent mounted upon the hand-lever G and adapted to engage a notched segment A² upon the bracket A'.

15 I is a bell-crank lever mounted upon a vertical pivot i and arranged in approximately the same horizontal plane as the lower end of the arm F' . The said pivot i is herein shown
30 as mounted in a depending bracket A^3 , attached to the frame A . Said bell-crank lever I is provided with an arm I' , arranged transversely with reference to the shaft C and the axle of the machine, and extending forward
35 with its free end suitably located to be connected with the cutter-bar of the machine, said cutter-bar being indicated by dotted lines at K , Fig. 1. Said bell-crank lever is also provided with a shorter arm I^2 , arranged
40 approximately at right angles with the arm I' , and connected at its free end by means of a connecting-bar L with the lower end of the arm F' of the sleeve F . From this construction it is entirely obvious that when the said
45 arm F' is oscillated a corresponding oscillatory movement will be transmitted through the medium of the bell-crank lever I to the cutter-bar K .

In Fig. 5 I have shown a modification of the scalloped driving-cam E and rocking lever C', 50 wherein the cam is located upon the drive-wheel B inside of the rocking lever or between the same and the wheel-hub. The cam-face is in this instance formed upon the exterior of the cam-ring; but the latter is scalloped and toothed in the same manner as before described, and operates in the same manner to give a rocking movement to the rock-shaft C. The wheel-hub A, the wheels D, D, and 55

The gear-teeth upon the wheels D D and cam E produce the same effect in both forms of the device shown, causing an equal and uniform rotation of both gear-wheels and an equal wearing of all the parts of the gear, as above set forth. 65

I claim as my invention—

1. The combination, with the frame and cutter-bar of a mower, of a drive-wheel provided with an annular scalloped toothed cam and a swinging lever provided with two toothed wheels or pinions upon its ends intermeshing with said toothed cam, substantially as described. 70

2. The combination, with the frame and cutter-bar of a mower, of a drive-wheel provided with a scalloped and toothed cam, a rock-shaft mounted on said frame and provided with a rocking lever, toothed pinions upon the ends of said lever engaging said cam, a longitudinally-grooved arm rigidly attached to said rock-shaft, a loose sleeve upon said rock-shaft provided with an arm adapted to engage the groove of the arm upon said rock-shaft, a hand-lever for moving said sleeve endwise upon the shaft, and a bell-crank lever, one arm of which is connected with the cutter-bar and the other with the arm upon the sleeve, substantially as described. 75
